By Munday, Clarke & Carpenter, Jr.

UNITED STATES PATENT OFFICE.

ALOYSIUS C. LIPPERT, OF KENOSHA, WISCONSIN, ASSIGNOR, BY DIRECT AND MESNE ASSIGNMENTS, TO THE NORLIPP COMPANY, OF CHICAGO, ILLINOIS, A CORPORATION OF ILLINOIS.

LATCHING DEVICE FOR RADIATOR CAPS.

Application filed August 11, 1924. Serial No. 731,288.

The present invention relates to radiator caps for automobiles and the like, and more particularly to the type of radiator caps adapted to be locked upon the radiator neck and which are provided with a hinged cover for closing the filling opening.

A primary object of the invention is the provision of a latching device for the cover of a radiator cap of this character which will be easy to operate and effective in action.

A further object is the provision of a latching device, in a radiator cap construction, which will be inexpensive to manufacture and which will not require frequent attention or replacement in service.

Numerous other objects and advantages of the invention will be apparent as it is better understood from the following description, which, taken in connection with the accompanying drawings, discloses a preferred embodiment thereof.

Referring to the drawings,

Figure 1 is a front elevation, partially broken away, of a radiator cap in which my invention is embodied;

Fig. 2 is an end elevation, partially broken away and shown in section, of said radiator cap;

Fig. 3 is a perspective view of a latch; and

Fig. 4 is a detail view of the actuating spring.

Upon said drawings, which illustrate the best manner in which I have contemplated applying the principles of my invention, the reference character 11 indicates the body of a radiator cap in which is positioned an inner collar, or adapter 12, having screw threads 13 adapted to fit upon the radiator neck, means (not shown) being provided to lock said body to said insert in such manner that rotation of the body will not unscrew the insert from the radiator neck. Inasmuch as the radiator cap assembly is thus permanently locked in place, it is necessary to provide means for readily opening and closing the filling opening to put water in the radiator, and for this purpose, a hinged cover 14 is provided, being hinged at the rear to upstanding lugs 15 by means of a pivot pin 16, which preferably extends only partially through one of the lugs 15 and is

counter-sunk in the other so that removal is rendered difficult, it being necessary to 55 complete the hole in the "blind" lug by means of a punch before the pin may be driven out.

An aperture 17 is provided in the center of the cover 14 to receive the stem of a 60 motometer 18, which is adapted to be locked to said cover in any preferred manner to prevent theft, provision being made, as has been heretofore stated, for preventing the removal of the cap itself from the radiator 65 neck. At the front of said cover, I provide a lug 19 and the lower outer edge of the cover is beveled, as indicated at 21, and adapted to tightly seat against a gasket 22, which has a shoulder 23 fitting upon the 70 top of the insert 12 and adapted to be clamped against an inwardly extending top shoulder 24 on the cap body 11. A protuberance 20 is provided upon the lug 19 and adapted to cooperate with a latch to be 75 hereinafter described, to hold the cover in closed position.

At the front of said cap body, a projection 25 is provided and may be of ornamental appearance and adapted to have a 80 name, or emblem plate 26, or the like, secured thereto if desired. A recess 27 is formed in the upper part of said projection and a pivot pin 28 has bearings in the stock at the sides of said recess. A latch 29 is pivotally mounted upon said pin 28, being provided with punctured lugs 31 at its lower end for this purpose. Said latch is preferably curved outwardly at the top, as indicated at 32, to facilitate manipulation thereof by the fingers, and it will be evident that the exposed portion of the latch may be ornamented in any desired manner, as by providing a contour at the top corresponding to the contour of the upper portion of the front projection 95 25 and name plate 26, it being noted that in the present instance the upper corners of the latch are rounded out, as indicated at 33, to correspond to the rounded out portions 34 of the plate 26, which latter is in the 100 general form of a keystone.

A spur 35 is provided on the rear side of the latch member 29, being formed, in the present instance, by slitting and projecting the material of said member, and this spur 105 is adapted to engage over the forward lug

19 upon the cover 14 when the latter is in closed position and said latch is forced rearwardly. A spring 36 is provided for the purpose of holding said latch normally in 5 closing position with the spur 35 engaging over the lug 19, and this spring is preferably coiled about the pivot pin 28, with prongs 37 extending upwardly in engagement with the front side of said plate and an extended 10 central portion 38 extending upwardly in contact with the front wall 39 of the recess 27, it being evident that the prongs 37 and 15 38 exert tension in the opposite extension 38 exert tension in the opposite directions, so that the latch is normally held 20 in the full line position shown in Fig. 2 and may be moved to the dotted line position shown in said figure for the purpose of opening 25 the cover to fill the radiator. An opening 41 extends from the recess 27 through to the bottom of the projection 25 and provides 30 means of access to the mechanism of the latching device. It will be evident from the foregoing that with the latching device provided by my invention, the cover 14 may be 35 quickly and easily opened and closed and will be normally held in closed position without likelihood of being accidentally opened by vibration of the car, or other accidental cause.

30 It is thought that the invention and its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

40 I claim:

1. In a radiator cap comprising a body attachable to the filler neck of a radiator and a cover hinged to said body and adapted to permit access to the radiator without removal 45 of the cap body from the filler neck, means for releasably fastening said cover in closed position, said means comprising a latch member pivotally connected to the cap body and at the front thereof, said member having a 50 part adapted to engage the top of the cover to hold the latter in closed position, said part being formed as a thumb-piece and extending vertically upward from its pivot, the engageable part of said thumb-piece being 55 above the cover and a spring associated with said latch member and adapted to urge the latter toward latching position.

2. In a radiator cap comprising a body attachable to the filler neck of a radiator and 60 a cover hinged to said body and adapted to permit access to the radiator without removal of the cap body from the filler neck, means for releasably fastening said cover in closed position, said means comprising a 65 latch member pivotally connected to the cap

body and at the front thereof, said member having a projecting part adapted to engage over the top of the cover and presenting a beveled surface adapted to be acted upon by the cover in closing to move the latch out 70 of the way, said part being formed as a thumb-piece and extending vertically upward from its pivot, the engageable part of said thumb-piece being above the cover and a spring associated with said latch member 75 and adapted to urge the latter toward latching position.

3. In a radiator cap comprising a body attachable to the filler neck of a radiator and a cover hinged to said body and adapted 80 to permit access to the radiator without removal of the cap body from the filler neck, means for releasably fastening said cover in closed position, said means comprising a latch member pivotally connected to the cap body and at the front thereof, said member having an integral projecting part adapted to engage over the top of the cover and presenting a beveled surface adapted to 85 be acted upon by the cover in closing to move the latch out of the way, said part being formed as a thumb-piece and extending vertically upward from its pivot, the engageable part of said thumb-piece being above the cover and a spring associated with said 90 latch member and adapted to urge the latter toward latching position.

4. In a radiator cap comprising a body attachable to the filler neck of a radiator and a cover hinged to said body and adapted to 100 permit access to the radiator without removal of the cap body from the filler neck, means for releasably fastening said cover in closed position, said means comprising a latch member pivotally connected to the cap body and at the front thereof, said member having a part adapted to engage the top of the cover to hold the latter in closed position and a spring mounted on the pivot of said 105 latch member and having opposed parts acting respectively upon the cap body and upon the latch member to urge the latter into latching position, said part being formed as a thumb-piece and extending vertically upward from its pivot, the engageable part of 110 said thumb-piece being above the cover and being spaced from a fixed part on the cap body whereby compression between said thumb-piece and said fixed part will disengage the latch.

5. In a radiator cap comprising a body attachable to the filler neck of a radiator and a cover hinged to said body and adapted to 115 permit access to the radiator without removal of the cap body from the filler neck, means for releasably fastening said cover in closed position, said means comprising a pivot pin mounted in a front part of the body, a latch member pivotally mounted 120 thereon and having a part adapted to engage 125

over the cover to hold the same in closed position, and spring means associated with said latch member and adapted to urge the same toward its latching position, said latch member having an engageable part extended upwardly in visible position at the front of the cap and a latching element on the same side of the pivot as said engageable part.

5

over the cover to hold the same in closed position, and spring means associated with said latch member and adapted to urge the same toward its latching position, said latch member having an engageable part extended upwardly in visible position at the front of the cap and a latching element on the same side of the pivot as said engageable part.

10

cover hinged thereto and having a latching lug provided with a protuberance on the top thereof, a pivoted latch member having a part adapted to engage over said protuberance to hold the cover down, said part being formed by shearing and forcing out 15 a portion of the latch.

6. In a radiator cap, comprising a body, a

ALOYSIUS C. LIPPERT.
